E. G. ROWLEY

TYPEWRITING MACHINE

Original Filed April 30, 1925

15 Fig Inventor:
Edward G. Rowley
by D. C. Hickley
Attorney

UNITED STATES PATENT OFFICE.

EDWARD G. BOWLEY, OF BELLEVILLE, NEW JERSEY, ASSIGNOR TO UNDERWOOD ELLIOTT FISHER COMPANY, OF NEW YORK, N. Y., A CORPORATION OF DELAWARE.

TYPEWRITING MACHINE.

Application filed April 30, 1925, Serial No. 26,886. Renewed January 28, 1927.

This invention relates to a sound-deadening casing for a portable typewriting machine, in which the machine is completely enclosed within the casing except for the 5 keyboard, which protrudes through the wall.

In my application No. 17,554, filed March 23, 1925, there is shown a casing for the purpose of deadening the noise of typewriter operation. In said invention the carriage of the machine is controlled from the outside of the casing by means of a hand-lever at the keyboard, the lever being operatively connected to the line-space devices of the carriage.

15 In this invention there is provided improved mechanism for controlling the movements of the carriage from the outside of the casing. The carriage-release mechanism comprises a bail-piece mounted in the casing 20 and operatively connected to a depressible exterior button mounted on the front wall of the casing. Said bail-piece extends substantially the full width of the casing and engages the carriage-release lever when operated by the button. The latter may be 25 held back by the left hand while the right hand manipulates the exterior carriage-driving handle to run the carriage to and fro without opening the casing.

30 Another feature of this invention relates to margin-gage devices or tabulating devices for locating the carriage. Upon a bail is an adjustable stop-device, co-operative with a fixed stop on the carriage, in such a manner that when the automatic stop-button is depressed the bail-piece carrying the stop-device is swung in front of the stop on the carriage simultaneously with the release of the carriage. The two buttons are operatively connected, so that they will simultaneously operate when the automatic stop-button is depressed, thus permitting the carriage to move to position.

Another feature of this invention relates 45 to means for facilitating the insertion of the machine in the casing and the removal therefrom. To this end, the front wall of the casing is provided with a slot the full width of the keyboard extension, to permit the placing of the machine in the casing vertically. The opening at the top of the slot between the keyboard and the top of the front wall is closed by means of a felt-lined front plate. The front plate is supported

by means of a metal strip fast thereto and 55 to which there are fast two headed studs engaging with slots in the front wall of the casing. The detachable front plate also serves to fasten the machine down upon its sound-deadening bed of thick felt.

60 Other features and advantages will hereinafter appear.

In the accompanying drawings,

Figure 1 is a plan view of the sound-deadening casing with the cover removed, and showing an Underwood portable typewriting machine operatively placed therein.

Figure 2 is a cross-sectional view, in elevation, through the line 2—2 of Figure 1.

Figure 3 is a detail, showing the carriage-stopping mechanism in its normal position, and the carriage-releasing mechanism in its operated position.

Figure 4 is a detail, showing the carriage-stopping mechanism in its operated position.

Figure 5 is a front view of the opening through which the keyboard protrudes, and shows the front plate closing the opening at the top thereof.

This invention is illustrated in connection 80 with an Underwood portable typewriting machine, and is for the purpose of deadening the noise arising from the operation thereof.

In small portable machines of this kind 85 it is sometimes desirable to remove the machine from the casing and then pack it into the portable casing, which forms a part of the equipment usually supplied with the machine. For this reason, it is advantageous 90 to insert the machine in the casing and remove it therefrom with little or no alteration thereof, and also to simplify the operation of installing the machine for use in the casing. The casing comprises a body-part 10 and a cover 11 rockably mounted on the body-part by means of hinges 12. The front wall of the casing is provided with a slot or opening 13 substantially the full width of the keyboard extension 14. In this 95 manner, the machine is placed upon a base-board 15 horizontally, and then the opening at the top of the keyboard is closed by means of a front plate 16 which also holds the machine in place. Said front plate is provided 100 with studs 17 fast thereto, and the studs are provided with a turned-down body 18 engaging with slots 19 in the front wall 20.

In order to prevent the emission of sound through the front plate 16, the same is provided with a layer 21 of sound-deadening material, glued or otherwise secured thereto.

5 The lower edge 22 of the plate 16 is designed to fit the outline of the upper edge of the front plate of the machine.

In the Underwood machine, there is provided a carriage 23 mounted upon rails, and 10 the carriage is arranged for letter-space travel at each key depression. In order that the carriage may be returned after each line of typing, there is provided mechanism which may comprise a hand-operable lever 15 24 fulcrumed on the front wall of the casing. The lever 24 is operatively connected to a shaft 25 by means of a gear 26 engaging with a pinion 27 fast to said shaft, which carries fast thereto a drum 28 around which a cord 20 29 is wound. Upon depressing the lever 24 the drum 28 will be caused to rotate, thus winding the cord therearound and pulling on the carriage toward the drum. The cord 29 is shown connected to the carriage at 30, but 25 obviously the same could be connected to the line-space lever 31, as illustrated in my above-mentioned application No. 17,554, in which other mechanism is shown for the purpose of improving the operation of the 30 carriage-return mechanism hereinbefore described.

In order to further eliminate the necessity of opening the cover to control the movement of the carriage, there is provided mechanism 35 whereby the carriage may be released from the escapement mechanism and then positioned by means of the lever 24.

In the Underwood machine there is provided an escapement gear 32 rotatably 40 mounted on the frame thereof. There is also provided a pinion 33 fast to the gear, and the pinion operatively meshes with a rack 34 which is releasable from the pinion by means of a lever 35. The lever 35 is rockably 45 mounted upon the platen-shaft 36 and engages the rack-supporting arms 37 at 38, the supporting arms being fulcrumed at 39 upon the platen-frame. In this invention there is provided mechanism for releasing the 50 lever 35 from the outside of the casing. Said mechanism may comprise a bail piece 40 rockably mounted on a shaft 41 fast to the end walls 42 of the casing, in a manner to depress the lever 35 when a button or finger-piece 43 collapsibly mounted on the front wall is operated. Said button 43 is operatively connected to the bail-piece 40 by means of linkage which may include an arm 44 fast to the bail-piece and a rod 45 fast to 55 the button and connected to the arm 44 at 46.

Another feature of this invention relates to automatic means for positioning the carriage relatively to the printing point, by simply depressing a button or finger-piece 47 60 mounted on the front wall of the casing.

To this end, there is provided a bail-piece 48, rockably mounted on the shaft 41. The bail-piece 48 is preferably of rectangular cross-section having a series of slots 49 cut therein to form a rack for receiving a stop-clip 50 resiliently held thereon. Upon depressing the button 47, which is fast to a rearwardly-extending rod 51, the bail-piece 48 is swung on its supporting shaft 41 from a position shown in Figure 3 to that shown in Figure 4, in which the bail-piece 48 is shown swung downwardly by the action of an arm 52 which forms an integral part thereof, and is operated by the rod 51 connected thereto at 53. By swinging the bail 48 to the position shown in Figure 4, the stop-clip 50 is brought in the path of a stop-device 54 fixed to the carriage, so as to arrest the same.

In order to render the carriage-stopping mechanism fully automatic, it is necessary to release the carriage simultaneously with the interposing of the stop-clip to arrest the carriage, and, to this end, one of the end pieces 55 of the bail 48 is provided with a finger 56, bearing upon the end piece 57 of the bail 40, so that, by the operation of the button 47, both bails will be rendered effective, but when the button 43 is operated, then only the bail 40 will be swung to release the carriage.

It will be understood that in order to further increase the efficiency of the sound-deadening casing, the front, rear and side walls thereof and the cover may be covered with layers of sound-deadening material, and that the machine may, by the same or any other method, be insulated from the base-board and secured thereto by means of a supporting member, the same or similar to that disclosed in my said application.

The carriage may be quickly positioned from the outside of the casing by simply depressing the carriage-release button with one hand while the carriage-return handle is 110 operated with the other hand against the pull of the carriage-feeding spring which draws the carriage in the opposite direction.

Variations may be resorted to within the scope of the invention, and portions of the 115 improvements may be used without others.

Having thus described my invention, I claim:

1. In a sound-deadening casing for a type-writing machine, said casing completely enclosing the machine except for the keyboard extending through an opening in front thereof, means for returning the carriage including an arm pivotally mounted on the side of said casing, and means controlled by a depressible button for releasing the carriage.

2. In a sound-deadening casing for a type-writing machine, said casing completely enclosing the machine except for the keyboard 130

extending through an opening in front thereof, means for returning the carriage including an arm pivotally mounted on the side of said casing, and means controlled by 5 a depressible button for releasing the carriage, said last-mentioned means including a bail-piece extending substantially the full width of the casing, and a button extending to the outside of the casing and effective to 10 rock the bail-piece, said bail-piece being effective to actuate upon the carriage-release lever of the machine.

3. In a sound-deadening casing for a type-writing machine, said casing completely enclosing the machine except for the keyboard extending through an opening in front thereof, means for returning the carriage including an arm pivotally mounted on the side of said casing, means controlled by a 15 depressible button for releasing the carriage, and means controlled by a second depressible button effective to automatically release the carriage and to stop it in a predetermined position relative to the printing point.

25 4. In a sound-deadening casing for a type-writing machine, the combination of a body-part and a cover, the body-part having an open slot substantially the full width of the keyboard-extension of the machine to facilitate the insertion of the machine in the casing, and detachable means co-operative with 30 said body-part for locking the machine in place in the casing and for preventing the passage of sound-waves through the portion 35 of the slot not closed by the keyboard-extension of the machine, said detachable means including a front plate fitting down upon the top edge of the front plate of the typewriter.

40 5. In a sound-deadening casing for a type-writing machine, the combination of a body-part and a cover, the body-part having an open slot substantially the full width of the keyboard-extension of the machine, and a 45 front closure for locking the machine in place and for preventing escape of sound-waves, said closure having headed studs fast thereto and slots in the front wall of the casing for receiving the body of the headed 50 studs, said closure occupying the full width of said slot above said keyboard and at its lower edge shaped to fit closely to the top edge of the front plate of the machine above said keyboard.

55 6. In a sound-deadening casing for a type-writing machine comprising a body-part and a cover therefor, the body-part having an opening at the front for the keyboard-extension to render the machine operable from the 60 outside of the casing, means for concomitantly line-spacing the platen and returning the carriage of the machine, means for releasing the carriage by the depression of an exterior button, and a tabulating device including means for releasing and positioning 65

the carriage by the depression of a second exterior button, both buttons mounted on the front of said casing.

7. In a sound-deadening casing for a type-writing machine comprising a body-part 70 and a cover therefor, the machine being operable from the outside of the casing, and tabulating means for releasing and then positioning the carriage by the depression of an exterior button mounted on the front of 75 the casing, said means including a bail-piece rockably mounted on the casing, means operatively connecting the button to the bail-piece, an adjustably mounted stop-device fast to the bail-piece and a fixed stop on the carriage and co-operating with the stop-device to arrest the travel of the carriage when the carriage is released.

8. In a sound-deadening casing for a type-writing machine comprising a body-part and a cover therefor, the machine being operable from the outside of the casing, means mounted upon and within the casing for releasing the carriage, a tabulating mechanism effective to operate said carriage-releasing means and including means for releasing and positioning the carriage by the depression of a button, said tabulating means including a bail-piece rockably mounted on the casing, means operatively connecting the button to the bail-piece, an adjustably mounted stop-device fast to the bail-piece and a fixed stop on the carriage and co-operating with the stop-device to arrest the travel of the carriage when the carriage is released, an exterior release-key mounted on the casing, and means for operatively connecting the exterior release-key to said carriage-releasing means.

9. In a sound-deadening casing for a type-writing machine comprising a body-part and a cover therefor, means for concomitantly line-spacing the platen and returning the carriage of the machine, means for releasing the carriage by the depression of a button mounted on the casing, and means for both releasing and positioning the carriage by the depression of a tabulating button, said last two mentioned means including a double bail arrangement effective respectively to release and to arrest the travel of the carriage.

10. A sound-deadening casing having a body-part and a cover therefor, in combination with a typewriting machine having a carriage arranged for letter-feed travel and means including a lever for releasing said carriage, means operatively connected to an exterior button in front of the casing for releasing said lever, and a carriage-tabulator including means controlled by another exterior button in front of the casing for releasing said lever and also arresting the travel of the carriage when the releasing lever is operated.

11. A sound-deadening casing having a 130

- body-part and a cover therefor, in combination with a typewriting machine having a carriage arranged for letter-feed travel and means including a lever for releasing said carriage, means operatively connected to a collapsible button in front of the casing for releasing said lever, carriage-tabulating means controlled by another button in front of the casing and means operatively connecting the tabulating button to the carriage-releasing lever in a manner to cause the concomitant release of the lever and the arresting of the carriage.
12. A sound-deadening casing having a body-part and a cover therefor, in combination with a typewriting machine having a carriage arranged for letter-feed travel and means including a lever for releasing said carriage, means operatively connected to a collapsible button in front of the casing for releasing said lever, and means controlled by another button in front of the casing for arresting the travel of the carriage when the releasing lever is operated, said last two mentioned means including a double bail arrangement, one of the bails being effective to release the carriage by bearing upon the carriage-release lever, and the other bail being effective to present a stop-device to the carriage to arrest its travel.
13. The combination of a sound-deadening casing, a typewriting machine therein, including a carriage inaccessible for operation, means within the casing for returning the typewriter-carriage, a lever exterior of said casing at one side of the machine for manipulation by one hand, carriage-releasing means mounted within said casing, and a button connected to said carriage-releasing means and mounted at the exterior of the casing for manipulation by the other hand of the operator, whereby by employing both hands the operator may adjust the carriage back and forth without first opening the casing.
14. In a combined typewriting machine and sound-deadening casing, said casing completely enclosing the machine except for the keyboard extending through an opening in the front of said casing, a stop traveling with the carriage of the machine, carriage-releasing mechanism, a bail extending along the interior of the casing and mounted thereon adjacent the traveling stop, said bail including a rack-portion, a clip-stop carried selectively by the rack-portion, means operable from the outside of said casing for moving said bail to present the clip-stop in the path of the traveling stop, and means for automatically releasing the carriage as the bail moves the clip-stop to effective position.
15. In a combined typewriting machine and sound-deadening casing, said machine including a carriage having a release key thereon, said casing completely enclosing the machine except for the keyboard extending through an opening in the front of said casing, a stop traveling with said carriage, a displaceable rod extending along the interior of said casing and mounted thereon adjacent the carriage-stop, said rod having transverse teeth, a clip-stop engageable with any of said teeth and carried by said rod into the path of the traveling stop, a second displaceable rod extending along the interior of said casing and mounted thereon in operating relation with said carriage-release key, and means operable from the outside of said casing for causing the stop-carrying rod to move into said path, and also for causing the second rod to operate said key to release the carriage.
16. In a combined typewriting machine and sound-deadening casing, said casing completely enclosing the machine except for the keyboard extending through an opening in the front of said casing and being removable from the machine, tabulating devices carried by said machine, co-operative tabulating devices carried by the casing, all of said tabulating devices being brought into co-operative relation when the machine is positioned within the casing, and means outside of said casing for controlling said devices.
17. In a combined typewriting machine and sound-deadening casing, said casing completely enclosing the machine except for the keyboard extending through an opening in the front of said casing, carriage-releasing mechanism, tabulating devices, means controlled from the outside of said casing for releasing the carriage without tabulating, and means also operable from the outside of said casing for controlling jointly the carriage releasing and tabulating devices.
18. In a combined typewriting machine and sound-deadening casing, said casing completely enclosing the machine except for the keyboard extending through an opening in the front of said casing, carriage-releasing mechanism, a stop traveling with said carriage, a displaceable rod adjacent said carriage-stop, an adjustable stop carried by said rod and movable by the latter into the path of the traveling stop, a second rod extending along the casing and operable to release the carriage, and means outside of said casing for operating the stop-carrying rod, the latter including means for operating the carriage-releasing rod.
19. In a combined typewriting machine and sound-deadening casing, said casing completely enclosing the machine except for the keyboard extending through an opening in the front of said casing, a stop carried by the carriage of the machine, carriage-releasing mechanism, means operable from the outside of said casing for controlling the releasing mechanism, devices carried by said

casing and including a stop interposable in the path of the carriage-stop to control the carriage-travel when said releasing means is operated, and means operable from the 5 outside of said casing for controlling said interposable stop.

20. In a combined typewriting machine and sound-deadening casing, said casing completely enclosing the machine except for 10 the keyboard extending through an opening in the front of said casing, carriage-releasing mechanism, and means for releasing the carriage with one hand and operating the released carriage with the other hand, including means for controlling said release mechanism, and also including means for moving the carriage to and fro in its released con-

dition, said controlling and carriage-moving means including actuating devices independently mounted on the outside of the casing, 20 one at each side of the keyboard-extension.

21. In a combined typewriting machine and sound-deadening casing, said casing completely enclosing the machine except for 25 the keyboard extending through an opening in the front of said casing, carriage-releasing mechanism, means operable from the outside of the casing for controlling said mechanism, and means also operable from the exterior of the casing but independently 30 of said controlling means for moving the released carriage to and fro.

EDWARD G. ROWLEY.
